(57) **CLAIM**

The ornamental design for an electric mixer, as shown and described.

DESCRIPTION

FIG. 1 is a front, right and top perspective view of an electric mixer, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is enlarged view of area "9" in FIG. 2.

The broken lines shown in the drawings illustrate portions of the electric mixer that form no part of the claimed design. The dash dot dash lines in the drawings are for the purpose of depicting the cut line of the enlarged view and form no part of the claimed design.
